UNITED STATES PATENT OFFICE

2,353,344

SHIRT AND COLLAR PROTECTOR

Stephen Lighter, Milwaukee, Wis.

Application October 25, 1943, Serial No. 507,552

5 Claims. (Cl. 229—87)

My present invention relates in general to improvements in the art of protecting laundered shirts or the like, and relates more specifically to an improved assemblage for supporting and maintaining the collars of shirts or similar garments against possible collapse or undesirable crushing and resultant wrinkling.

The primary object of this invention is to provide a new and useful shirt and collar protector which is simple in construction and highly efficient in use.

In my prior Patent No. 2,243,350, granted May 27, 1941, I have shown and described a protective wrapper and retainer for maintaining a laundered shirt in neatly folded condition and in proper shape, by utilizing a shirt embracing band surrounding the folded shirt and having a panel and side tabs associated therewith and extending upwardly from the central portion of the front section of the band, this panel and tabs being cooperable with the forward part of the exterior of the collar band and with the inner surfaces of the collar lapels so as to eliminate danger of collapse and possible crushing of the collar. While this earlier patented structure was relatively satisfactory, it lacked means for positively holding the collar supporting panel and tabs in snug engagement with the collar band and lapels, and in my subsequent Patent No. 2,327,196, granted August 17, 1943, I provided instrumentalities for automatically and positively maintaining the collar supporting panel and tabs in elevated position so as to more thoroughly and effectively protect the collar assemblage. In these prior patents I also revealed means in the form of an elongated plate connected medially with the upper end of the protective panel and foldable within the collar band for protecting and supporting the interior of this band, and while such an internal supporting plate cooperating with a panel confined between the exterior of the collar band and collar lapels has heretofore been used extensively, the prior assemblages of this type did not make adequate provision for maintaining the inner supporting plate in snug engagement with the collar band so as to provide maximum support for the latter.

It is therefore a more specific object of my present invention to provide an improved shirt collar protector and support of the type having an inner collar band engaging plate connected to an outer collar band engaging panel confined beneath the collar lapels, and wherein the inner plate is automatically forced into snug coaction with the interior of the collar band when the

protective supporting assemblage is applied to a laundered shirt and collar.

Another specific object of this invention is to provide improvements especially applicable to my two prior patented shirt and collar protectors above identified, whereby the operation of such devices is considerably improved at no additional cost.

A further specific object of the invention is to provide an improved shirt wrapper and protector which can be manufactured of stiff paper with minimum waste of stock, and which is also readily and conveniently applicable to a folded and laundered shirt or the like, to maintain the same in neatly folded condition and protected against undesirable crushing and wrinkling.

Still another specific object of my invention is to provide a new and useful shirt collar protector which may be formed of a single blank of cardboard or the like, and which functions to automatically and most effectively support and protect the shirt when the protector is assembled upon the collar.

An additional specific object of the present invention is to provide a shirt and collar protecting and supporting assemblage which is highly attractive in appearance, effective in use, and which can also be manufactured and sold at moderate cost.

These and other objects of the invention will be apparent from the following detailed description.

A clear conception of the features constituting the present invention, and of the mode of constructing and of applying the improved shirt and collar protectors, may be had by referring to the drawings accompanying and forming a part of this specification wherein like reference characters designate the same or similar parts in the various views.

Fig. 1 is a plan view of one of the improved shirt and collar protectors, before being applied to a shirt;

Fig. 2 is a plan view of a typical folded shirt having the folding board still in place, and showing one of the shirt and collar protectors of the type shown in Fig. 1 superimposed upon the shirt preparatory to assembling the protector;

Fig. 3 is a perspective view of the finally enwrapped and protected folded shirt of Fig. 2, with the folding board removed;

Fig. 4 is a plan view of a modified improved shirt and collar protector, in flat condition and before being applied to a shirt;

Fig. 5 is a plan view of another typical folded

shirt having the folding board still disposed therein, and showing the modified type of protector of Fig. 4 superimposed upon the shirt preparatory to final application of the protector; and

Fig. 6 is another perspective view of a finally protected folded shirt, with the protector of Figs. 4 and 5 applied thereto.

While the invention has been shown and described herein as being formed of stiff material such as cardboard stock and especially adapted to cooperate with folded shirts of a particular style, it is not my desire or intention to thereby unnecessarily restrict the scope or utility of the improvement.

Referring to Figs. 1 to 3 inclusive of the drawings, the improved shirt wrapper and protector disclosed therein is primarily cooperable with a freshly laundered shirt 9 which has been neatly folded about a flat folding board 10 and is provided with a collar consisting of an inner band 11 and an outer portion 12 foldably connected to the upper edge of the band and having front wings or lapels 13 extending toward the bosom of the shirt 9. The improved protector specifically shown in Figs. 1 to 3 inclusive, comprises in general a laterally elongated retainer 14 formed to extend transversely across the bosom 15 of the folded shirt 9 below the two-part collar; a relatively narrow panel 16 projecting upwardly from the center of the upper front section 17 of the retainer 14; a pair of supports 18 connected to and forming an integral part of the panel 16 and extending laterally away from the opposite sides of this panel, each of these supports 18 having its end 19 fartheset from the panel 16 recessed for interlocking coaction with notched portions 20 formed directly on the retainer 14 so as to maintain the panel 16 in elevated condition relative to the plane of the shirt bosom 15; a transverse plate 21 swingably connected at its medial portion to the upper end of the central panel 16 and being foldable within the collar band 11; and a pair of hook elements or wings 22 formed integral with the upper portion of the panel 16 and being formed for interlocking coaction with notches 23 formed on the medial portion of the transverse plate 21.

The improved shirt and collar protector of Figs. 1 to 3 inclusive may be formed of a single sheet of carboard or the like, and is constructed as a band adapted to snugly embrace a shirt 9 with the opposite ends of the retainer 14 interlocked at the back of the shirt as in Fig. 3. The central panel 16 is slightly tapered as shown and is connected with the retainer 14 along a score line 24 so as to permit the panel to be elevated and to engage the upwardly inclined outer front surface of the collar band 11. The lapel engaging supports 18 which extend laterally away from the panel 16 between the collar band 11 and the outer collar 12, may also be hingedly connected to the panel along score lines 25, but these are not essential. The supports 18 may be cut directly from the stock of the transverse retainer 14, thereby leaving upwardly projecting portions 26 at the opposite sides of the front section 17, which serve to ultimately protect the shoulder portions of the folded shirt 9. The recessed end portions 19 of the supports 18 are formed to interlock with the notches of the inwardly extending resilient portions 20 of the retainer 14, so as to hold the panel 16 in elevated position and the supports 18 against the inner

or rear surface of the lapels 13 when the protector is finally assembled upon the shirt.

The collar band engaging plate 21 is formed integral with the upper extremity of the panel 16 and is adapted to be folded within the collar band 11 as shown in Fig. 3, and the hook elements or wings 22 are cut out of the body of the transverse plate 21 and are of such form that they produce the central notches 23 in this plate. There need be no definite score lines between the plate 21 and the panel 16, nor between the wings 22 and the panel 16, and when the panel 16 has been erected in easel formation with respect to the central portion 17 of the retainer 14, and the plate 21 is swung into the collar band 11, the hooks on the wings 22 will automatically engage the recesses 23 and will force the plate 21 into snug engagement with the upstanding inner surfaces of the collar band 11, as clearly shown in Fig. 3. Since the engagement of the outer ends 19 with the notches 20 and the engagement of the hooks formed by the wings 22 with the notches 23 is automatic, the improved shirt and collar protector can obviously be quickly applied to a shirt 9 with minimum effort.

In some cases it may be unnecessary to provide a shirt embracing retainer 14 such as shown in Figs. 1 to 3 inclusive, and in that event the lower portion of the retainer 14 may be omitted. Such a modified structure is depicted in Figs. 4 to 6 inclusive, and in the modified assemblage the panel 26 is provided with lateral extensions 27 which are adapted to be interposed between the collar band 11 and the outer collar portion 12. The upper end of the panel 26 is again integrally connected to a transverse plate 21 and is provided with clamping wings 22 adapted to engage the notches 23 formed on the plate 21. When assembling this modified structure upon a shirt 9, the panel 26 should be moved upwardly with the lateral extensions 27 thereon passing beneath the collar lapels 13, as illustrated in Fig. 5. When the panel 26 and lateral extensions 27 have been disposed beneath the outer collar portion 12 and the inner collar band 11 as in Fig. 6, the plate 21 may again be swung into the interior of the collar band 11 and the hook portions of the wings 22 will likewise engage the notches 23 and will clamp the projecting opposite end portions of the plate 21 into snug engagement with the inner forward portions of the collar band 11. This hooking and retaining action takes place automatically as the plate 21 is swung within the collar band 11, and this modified collar protector can therefore be quickly and conveniently applied to a shirt 9.

From the foregoing detailed description it will be apparent that my present invention provides an improved shirt and collar protector which is extremely simple in construction and highly efficient in use. The improved device besides maintaining the outer collar and the collar lapels in neat condition, also prevents the collar from being readily collapsed by virtue of the fact that the inner plate 21 is held firmly into snug engagement with the inner surface of the collar band 11. The collar band is in fact clamped between a rigid easel and the plate 21, thus providing an extremely sturdy support. The improved device can be quickly and conveniently applied to a shirt and the wings 22 provide an added attraction thereby enhancing the aesthetic appearance and sales appeal. Both of the improved collar protectors can obviously be manufactured at moder-

ate cost, and may be provided with suitable advertising and instructional printing or other decoration. The improved assemblage has proven highly satisfactory in actual use, and is especially applicable to shirt and collar protectors of the types covered by my prior patents hereinabove referred to.

It should be understood that it is not desired to limit this invention to the exact details of construction or to the precise mode of use, herein shown and described, for various modifications within the scope of the appended claims may occur to persons skilled in the art.

I claim:

1. A shirt collar protector comprising, a panel formed for coaction with the outer front portion of the collar band of a folded shirt beneath the outer collar and collar lapels, a collar band supporting plate swingably connected at its medial portion to the upper central portion of said panel, and a pair of hook elements formed integral with and disposed on opposite sides of the medial connection between said panel and plate, said elements being directly engageable with adjacent portions of said plate to clamp the latter against the interior of the collar band.

2. A protector as per claim 1, characterized thereby, that the hook elements are rearwardly

bendable and resiliently cooperable with adjacent relatively inclined portions of the plate to automatically clamp the plate against the interior of the collar band of the shirt when the plate is swung toward the panel and against the interior of the collar band.

3. A protector as per claim 1, characterized thereby, that the hook elements are resiliently connected to and extend laterally away from the connection at the upper part of the panel, and that the medial portion of the plate is provided with lateral notches with which the hook elements are interlockable when the hook elements are bent rearwardly during assembly.

10 4. A protector as per claim 1, characterized thereby, that the panel and the plate and the hook elements are all formed of a single sheet of stock, and that the hook elements are derived from the body of the plate so as to produce the 20 interlocking notches.

15 5. A protector as per claim 1, characterized thereby, that the hook elements of the assembled structure extend rearwardly across the upper ends of the outer panel and of the inner supporting plate and coact therewith to provide a rigid 25 tripod for maintaining the shirt collar in shape.

STEPHEN LIGHTER.
